UNITED STATES PATENT OFFICE.

ISAIAH H. FARNHAM, OF PORTLAND, MAINE.

TELEPHONE SYSTEM AND APPARATUS.

SPECIFICATION forming part of Letters Patent No. 281,478, dated July 17, 1883.

Application filed April 2, 1883. (No model.)

To all whom it may concern:

Be it known that I, I. H. FARNHAM, of Portland, in the county of Cumberland and State of Maine, have invented certain Improvements in Telephone Central-Office Systems and Apparatus, of which the following is a specification.

My invention relates to telephone-exchange systems, and more especially to certain special organizations, arrangements, and devices whereby the manipulations of the central office may be performed with increased celerity and certainty, and whereby the noise and confusion inseparable from such manipulations are materially diminished.

The specific aim of my invention is to provide increased facilities for the interconnection of subscribers' lines, especially when such lines enter the central station upon different switch-board sections, and also to provide suitable indicating devices, whereby, when a connecting bar or line common to all of the switch-sections is in use by any one of the said switch-sections, the fact may be at once indicated to all, the indication of such use continuing so long as the use of the connecting-bar continues, and ceasing upon the discontinuance thereof.

It has been found very convenient in large telephone-exchanges to divide the entering lines into groups of any desired number, each of the said groups being connected with a separate section of switch-board and assigned to the care of an operator. It is furthermore customary to provide each of the said switch-sections with a complete outfit of switching, signal receiving and transmitting, and supervising apparatus, so that as long as the sub-stations connected with any one section desire only to communicate with other sub-stations connected with the same section each switch-section is practically an exchange organization complete in itself. It is evident, however, that as the aggregate number of subscribers connected with the other switch-sections must greatly preponderate over those of any one section the great majority of communications will be with sub-stations connected with other switch-sections. Connecting devices are therefore essential which extend from each board to every other board, and these may, and generally

do, assume the form of metal bars or strips extending transversely across the several switch-boards, and connected with the corresponding connecting-bars of other boards by suitable wires, although they may, when desired, simply be socket-plates similarly connected, in which case they are united with the line-wires by flexible cords and plugs. A definite number of these connecting bars or plates are assigned exclusively for the local work of each switch-section—that is, if any sub-station on any board calls for another sub-station on the same board, these local bars are used. Consequently they begin and end on their own board, and have no connection with the connection-bars of other boards. For interconnection between the different boards, other bars are assigned, and upon each board a certain number of bars are united with a corresponding number upon every other board. Thus the switch-board A, besides being provided, for example, with ten local connection-bars, may also be provided with four connection-bars to switch-board B, four more to C, and so on, *ad libitum*, each other switch-board in the exchange-office being arranged on a similar plan. Experience has proved that the number of connecting-bars between any two boards must be kept at a very low limit, as otherwise the boards will assume such bulky and unwieldy proportions as to be unmanageable. On this account the number of bars between board and board does not ordinarily exceed four. Yet it is also obvious that this defect or disadvantage is one which must rapidly increase as the subscribers' lines and the number of sectional switch-boards increase, and that, furthermore, even when as many as four connecting-bars are allowed between each two boards, circumstances must frequently occur when a greater number than four become absolutely, although temporarily, necessary, with no alternative in the event of their absence except inordinate delay. By my invention I provide for such emergencies without any extensive increase in the size, bulk, or expense of the apparatus.

To this end my invention consists, first, in the combination, with a series of local connection-bars and a series of connection-bars extending from each sectional switch-board to

each other sectional switch-board—that is, one series from each board to every other board—of a third series common to and extending between all of the switch-boards.

5 It consists, secondly, in the combination, with a series of connecting-bars common to and extending between all of a number of switch-boards, of a series of circuit-closers and indicating-annunciators at each switch-board, 10 whereby the use of any of the said extra connecting-bars at any one of the switch-boards may be instantly indicated to each and all of the other switch-boards.

It consists, thirdly, in certain arrangements 15 of the circuits and circuit-closers with reference to the said connecting-bars, whereby the act of employing the connection-bar is caused to automatically actuate the circuit-closer of the indicator-circuit appertaining to the said 20 bar.

It consists, fourthly, in a specific construction 25 of the indicating-annunciators which I employ, whereby a greater degree of sensitivity is attained, and whereby I am enabled to operate efficiently a considerable number 30 of annunciators in and upon the same circuit.

It consists, finally, in certain details of construction and arrangement which will be hereinafter described, and which will be more specifically set forth in the claims at the end of this specification.

In the drawings which accompany and form a part of this specification, Figure 1 is 35 a diagrammatical representation of a series of four sectional switch-boards in a telephone central office, the whole being provided with connecting-bars common to all, and with devices to indicate their use in accordance with 40 the terms of my invention. Fig. 2 is a sectional side elevation of the form of annunciator which I prefer. Fig. 3 is a front elevation of the same. Fig. 4 shows a detail illustrating the automatic operation of my invention, taken on the line $y-y$ of Fig. 5; and Fig. 5, another detail of the same, the movable portion 45 of the circuit-closer being hung from a suitable support, and capable of being operated from any part of the sectional switch-board.

50 In Fig. 1, A, B, C, and D represent the different sectional switch-boards, which may be at any convenient distance from one another. Since the different subscribers' lines have no specific relation to my invention, they are not 55 shown.

As hereinbefore indicated, I provide connecting bars or strips of three different characters: first, bars for local connections, these being represented by the bars a ; second, separate series of bars from each switch-board to each other switch-board. In the drawings these are represented by b . It will be observed that I have in the said drawings, for greater clearness, carried out the connections in the 65 board A only. I have, moreover, only shown one strip or bar connecting with board B, one with C, and one with D, whereas in prac-

tice several bars of each board would be so connected. The principle, however, is the same, the difference being only in degree. A 70 third series of connecting-bars, c , are shown as extending throughout all the switch-boards from A to D, and irrespective of the number of the said boards. These bars, which are the only ones which are common to all the boards, 75 and which are capable of being used by all of them, are to be used as a medium of communication between any two switch-boards only when all the others between the said two boards are already occupied. Any desired number 80 of these common connecting-bars may of course be used. It now becomes necessary that when any of the common connecting-bars are in use between any two switch-boards the other switch-boards shall be notified of such occupation, in order that they shall not attempt a 85 duplicate occupation of the same, which would of course be equivalent to a cross or contact between the several line-wires concerned. For this purpose I provide each sectional switch-board with a series of annunciators, g , equal in number to the common connecting-bars. In the drawings, as I have shown three of the 90 said bars and numbered them 1, 2, and 3, so I also have shown three annunciators at each 95 board, and have designated them as g' , g'' , and g''' . At each switch-board I also place a series of circuit-closers, each consisting of a button-switch, e , and contact piece or stud f therefor. These also correspond to the several common connecting-bars, and are consequently 100 designated, respectively, e' , e'' , and e''' , and f' , f'' , and f''' . All of the button-switch pivots at each switch-board are united and connected with ground-wires 1, 2, 3, and 4.

E is a voltaic battery or other source of current electricity, grounded at one of its poles and united at the other with a wire, h , which divides into three branches, 10, 9, and 8. The branch 10 passes through the electro-magnet 110 of the annunciators g' of the switch-boards A, B, C, and D, successively, and, after passing through the coils of the last annunciator, returns by the wire 5 to the stud f' at the board A, the said stud forming a normally-open terminal therefor. It also touches or is branched into electrical connection with the stud f' at all of the switch-boards. The branch battery-wire 9 also passes successively through the helices of the annunciators g'' of A, B, C, and 115 returns by wire 6 to the stud f'' at each, touching *en route* all the studs f'' . The branch battery-wire 8 in like manner includes all the annunciator-magnets g''' , and returns by wire 7 to the stud f''' at A, touching *en route* at the 120 studs f''' at all of the switch-boards. Thus for each of the common connecting-bars 1, 2, and 3, I provide an annunciator and means for closing the circuit of the same at each sectional switch-board. The several annunciators may, if desired, when actuated, show a number or any other prearranged device to indicate the special connecting-bar which they 125 represent; or it may be understood that the

upper annunciator represents always the upper bar, the second indicator the second bar, and so on.

In the operation of my invention let it be supposed that a line entering the board A is to be placed in communication with a line entering at D, and that all the special connecting-bars between A and D are already occupied. It is therefore necessary to use one of the through connecting-bars, which is accordingly done; but as the same contingency is at any time likely to arise between any other two boards, as soon as the connection is made the operator at A, who has employed the connecting-bar 1, now turns his little switch-button *e* onto the stud *f'*, thus completing the battery-circuit through all the annunciators *g'* which correspond to that bar, the said annunciators thereupon becoming operative, and indicating to all switch-boards that connecting-bar 1 is in use, and is thus blocked, and may not be used by any other operator until the block-signal is withdrawn. When the connecting-bar is once more at liberty, it is the duty of the operator who has blocked it by the indicating-signal to turn his button-switch back immediately, which opens the circuit and withdraws the indicating-signals. Of course, if the connecting-bar No. 2 is used, the annunciators *g'* will also be employed, and in like manner the circuit-closers and annunciators employed will invariably correspond with the number of the connecting-bar used. The form of annunciator which I have found to be most convenient, and which I prefer to employ, is that which is shown in Figs. 2 and 3. It is specially adapted for use in this combination by reason of the facility with which it withdraws the signal when the circuit is opened.

The construction of this annunciator is as follows, although it may be greatly varied without departing from the principle employed:

A suitable case, F, is fitted with a glass front, *i*, and a short distance therefrom a steel needle, *j*, magnetized either permanently or by induction, is delicately pivoted in a plate of brass, *k*, or other suitable support. Immediately behind the said support is an ordinary electro-magnet, M, which, by means of a screw, *p*, working in a threaded chamber, *n*, fitted to the rear partition, *m*, is capable of adjustment to and from the needle. The end of the screw-spindle *p* may be made to turn somewhat loosely in the block *l*, so that the back and forward adjustment shall not tend to produce a rotary movement of the electro-magnet. The battery operating the indicators may sometimes weaken and fail to produce a deflection of the needle square across the face of its aperture or window. Moreover, if it appear desirable, for uniformity of appearance, to bring all the needles to a particular point on the dial, this may be effected in either case by providing a rotary adjustment for the electro-magnet, whereby it is enabled to act more or less powerfully on the said needle. The elec-

tro-magnet may thus be turned on its axis, as shown in dotted lines in Fig. 3, (which is a section taken on the line *z z* of Fig. 2,) by loosening the lock-nut *o*, and then turning the chamber *n* bodily in the recess of the partition *m*. The needle may also be slightly weighted, if necessary, at its lower end; but this will not usually be requisite, and I do not prefer it, as the sensitiveness of the annunciator is thereby impaired. By the use of this annunciator I am enabled to operate the hereinbefore-described signaling system in connection with a large number of switch-boards, using a comparatively small battery-power. I do not, however, restrict myself to its use, as in some cases I may find it convenient to use other forms. I have also devised means whereby the block-signal may be operated automatically by the same movement that is made to connect any two lines together. This modification is represented in Figs. 4 and 5.

In Fig. 4, G is a section of the switch-board, and the connecting-bars *q* are shown in section thereon. These are perforated at suitable distances apart by plug-holes *r*.

s s represent the incoming line, which expands into a kind of spring-jack, *s'*, adapted to make contact, as shown, with the plug *P*. The circuit-closers are fixed immediately behind the plug-holes, and may consist, as shown, of an insulating-support carrying a series of contact-springs, *x*, one for each plug-hole, while the complementary contact is furnished by the pivoted plate *w*, which may stretch across the entire switch-board section, so as to be operated by any or all of the plugs of the individual connecting-bars employed. A piece of non-conducting material, *w'*, is let into the said plate *w* opposite each plug, whereby the circuit-closing apparatus and indicating-circuit are completely insulated from the line-circuits. The pivoted plate *w* is suspended by the hangers *v*, and by means of the wire 10 is connected with the ground-wire, as shown in the manual circuit-closer Fig. 1. The circuit-springs, by means of the wire 11, lead to the annunciators belonging to their special connecting-bar, and thence to the battery. I may of course substitute a metallic for a ground signaling-circuit, and the same would in some cases be preferred; or I may, if I prefer, utilize the connecting-bar *q* itself as one side of the indicating-circuit; but this is not generally advisable, as it is liable to produce confusion between the main and the indicating circuits.

I am aware that heretofore signaling-circuits have been arranged between the different sectional switch-boards of a telephone central office; but they have uniformly been for the purpose of communication between the different operators, and have been adapted to produce transient signals only. On the contrary, my invention contemplates the establishment of a block-signal to be maintained during the entire time that the common connecting-bars are in use, and is intended, moreover, to subserve

the purpose of an indicating-signal, and not in any way to aid in communicating between the operators.

I make no claim herein to an annunciator of the special character described—namely, an annunciator consisting of an electro-magnet capable of horizontal and rotary adjustment, and provided with a magnetic and polarized needle pivoted in front of or between the poles of the electro-magnet, since I reserve the same to form the subject-matter of a separate application for Letters Patent.

Having now fully described my invention, I claim—

1. The combination, in a telephone-exchange system in which the incoming lines are grouped upon separate sectional switch-boards, of a series of local connection bars or plates, whereby any line may be united to any other line entering at the same switch-board, a number of series of interconnection bars or plates extending between the different switch-boards, (one series of the number between each two of the said switch-boards,) whereby a line entering at any switch-board may be connected with a line at any other specific switch-board, and a series of through-connection bars or plates common to and extending successively and serially to each and all of the switch-boards, whereby lines entering at any two different switch-boards may be connected when all of the bars extending exclusively between the said switch-boards are occupied, substantially as described.

2. The combination, in a telephone-exchange system of the character hereinbefore specified, of a series of local connection-bars, a number of series of interconnection-bars, whereby each switch-board is independently connected with each other switch-board, a series of through connecting-bars, each bar extending to all and adapted to be used by all of the said switch-boards, and means, as specified, whereby the use of the common or through connecting-bars by any two of the switch-boards is indicated to all of the other switch-boards, substantially as described, and for the purposes set forth.

3. The combination, in a telephone-exchange system of the character specified, of a series of local connection-bars, a number of series of interconnection-bars, each two switch-boards being independently connected by a single series, a series of through connecting-bars connecting with all and adapted to be used by all of the said switch-boards, and means, as indicated, whereby the use of the through connecting-bars by any two of the switch-boards may be signaled to all of the other switch-boards, and whereby, when the said use is discontinued, the signal indicating the same is automatically withdrawn, substantially as described.

4. In a telephone-exchange system in which the subscribers' lines are grouped upon a number of separate and independent switch-boards, the combination of a series of connecting-bars,

or their equivalents, extending to and between all of the said switch-boards and common to all, with a series of indicating-circuits, (one for each of the said connecting-bars,) each of the said circuits being provided at each and all of the switch-boards with a circuit-closer and an annunciator or indicator, whereby when any of the connecting-bars are in use between any two of the switch-boards the same may be indicated to all of the other switch-boards by closing the indicating-circuit of the said bar, the discontinuance of the said use being correspondingly indicated by opening the said circuit, as described.

5. The combination, in a telephone-exchange system, of a series of sectional switch-boards, each adapted for the reception of a definite number of entering line-wires, with a series of connecting-bars extending to and between all of the said switch-boards, a series of indicating-circuits therefor, one for each through connecting-bar, each indicating-circuit being provided at each switch-board of the system with an indicator and a circuit-closer, whereby the use of any of the connecting-bars by any switch-board may be indicated simultaneously to all of the others, and a battery common to all of the indicating-circuits, substantially as specified.

6. The combination, in a telephone-exchange system, of a series of sectional switch-boards and a series of connecting-bars common to all of the said switch-boards, with a series of indicating-circuits therefor, (one for each of the said connecting-bars,) each of the said circuits extending from a battery successively through a series of indicators or annunciators, one at each switch-board, and then branching to each of a series of contact-points, one at each switch-board, and terminating in a normally-open condition at the last of the said contact-points, and at each switch-board a series of circuit-closing buttons or springs permanently united with ground-wires or with a return battery-wire, whereby, when any of the common connecting-bars are in use by any of the switch-boards, the same may be indicated to the others by closing the corresponding indicating-circuit through all of the annunciators thereof by means of any of the said circuit-closers, as described.

7. The combination of a series of sectional switch-boards and a series of connecting-bars common to all of the said switch-boards, with a series of indicating-circuits therefor, one for each of the said connecting-bars, an annunciator at each of the said switch-boards included in each indicating-circuit, and automatic circuit-closing devices, substantially as indicated, whereby the insertion of a connecting-plug in any of the said connecting-bars is automatically adapted to close the indicating-circuit and give the occupation-signal to all of the other boards, as specified, and for the purposes described.

8. The combination of a series of connect-

ing-bars extending between a number of switch-boards and common to all of the said switch-boards, with a series of indicating-circuits therefor, one for each bar, a polarized annunciator at each of the said switch-boards included in each indicating-circuit, and a series of circuit-closers, one for each circuit, at each switch-board, as described.

9. The combination of a series of switch-
10 board connecting-bars with indicating-circuits therefor, one for each bar, and automatic circuit-closers located in the rear of the connect-

ing-bars, and adapted to be operated by the insertion of a plug in the said connecting-bar, as described.

In testimony whereof I have signed my name to this specification, in the presence of two subscribing witnesses, this 29th day of March, A. D. 1883.

ISAIAH HENRY FARNHAM.
